LOUIS DOMINIQUE JOSEPH ARMAND DUNOYER, OF NEUILLY-SUR-SEINE, FRANCE

ILLUMINATING DEVICE FOR PROJECTING SOUND FILMS

Application filed October 30, 1930, Serial No. 492,319, and in France November 8, 1929.

It is known that all so-called sound films carry a more or less broad band (which may in certain cases occupy the full width of the film) wherein the original sound vibrations are recorded.

Two types of records may be used.

1. In the so-called variable density type, the photographic density of the sound band is the same throughout the width of the band, but it varies in a continuous manner longitudinally of the band, its variations corresponding, as to frequency and to intensity, to the sound vibrations recorded.

2. In the so-called constant density type, the sound band is divided lengthwise in two parts in each of which the density has a constant value which is different for each part, these parts being separated by an undulating curve the undulations of which correspond to the sound vibrations recorded.

When it is desired to reproduce the sounds recorded, the film is threaded through the projecting apparatus while a light beam is caused to pass through it, said beam passing throughout its breadth, but only over a very small height so as to ensure a correct reproduction of the sounds. Such a correct reproduction requires indeed that the intensity of the beam, after passing through the film, follows the smallest variations of the density of the film, in the case of the variable density method or of the width of the two parts of uniform opacity, in the case of the constant density method. By reason of the speed used for the threading of the films and of the frequency of the sound vibrations which it is necessary to record in order to obtain good results (the higher harmonics of high frequency playing a very important part in certain noises and in sibilant syllables), the height of the sound band to be passed through by the light beam should not be above about 0,05 m/m. After passing through the film, the light beam is received in a photo-electric cell the current in which is

thus modulated in a manner corresponding to the intensity of the beam. This current, after amplification, is sent into a loud speaker.

In order to limit to a height of 0,05 m/m the portion of the band through which the light beam passes, the usual method used consists in making the film rub over a slot having the width of the sound band and the desired height, and in projecting on this slot the image, which is larger than the slot, of a comparatively wide light source. But the use of such a slot shows serious drawbacks.

a. dust accumulates rapidly on its edges and modifies sometimes in an irregular manner its useful surface; the result thereof is a continual reduction in the volume of the sound transmitted and, what is worse, the production of parasitical noises when the dust deposit is irregular;

b. the dust soon scratches the film which not only damages the latter but also produces parasitical noises;

c. the slot makes generally an insufficient use of the light provided by the source, because the image of the latter overlaps the surface of the slot to a considerable extent, only a small portion of the light producing the image passing thus through the slot;

d. with the sources of light used nowadays, for instance a spirally wound electric filament, it is often difficult to obtain a uniform illumination of the slot throughout its length. This shows no inconvenience with the variable density method but shows obviously very serious drawbacks with the constant density method;

e. lastly if, in order to remove some of these drawbacks, it is attempted to prevent the film from rubbing over the slot, other difficulties are encountered: if the beam is widely open and consequently concentrates much light on the film, the height illuminated on the film becomes much larger, and the higher harmonics are no longer reproduced. If, on

the contrary, the light beam is narrow enough for a slight spacing between the slot and the film to not substantially cause an increase in the illuminated height, the amount 5 of light transmitted by the beam is small, and the photo-electric currents become too weak.

My invention has for its object an optic illuminating device for the sound band, the 10 parts of said device being designed in a manner such as will remove these drawbacks and provide at the same time the best efficiency for the source of light. Owing to the particular source of light used, the slot has no 15 action on the light beam projected on the film. Moreover, the light forming the image of the source is used entirely. Lastly, the illumination of the sound band is uniform throughout its breadth.

20 The light source is constituted by a perfectly rectilinear incandescent filament, a perfectly correct image of which is formed on the film by means of a short focus photographic object-glass, this image having the 25 same width as the sound band and being exactly perpendicular to the longitudinal axis of the band. The filament having a diameter under 0,2 millimeter, it is sufficient for its image to be at least four times smaller for the 30 height of the illuminated band to be under 0,05 millimeter, the length of the filament being chosen such that the band is illuminated throughout its width.

However, and this forms an important object of my invention, particular arrangements should be taken for the illuminated zone to be as well defined as by a slot. To accomplish this, it is necessary for the image of the filament to show no aberration. Now, 40 it is not sufficient therefor for the photographic object-glass to be properly corrected. The light issuing from the filament first passes through the walls of the bulb containing it and the walls of usual bulbs, of 45 blown glass, show always unevennesses and non-homogeneous portions which render partly useless the corrections given to the object-glass and make these corrections practically impossible, as these unevennesses and 50 these non-homogeneous portions are irregular and cannot be foreseen. The bulb according to my invention does not show this drawback. Its wall is made in the part, through which the light used passes, of a 55 plate-glass with parallel surfaces optically machined and of known thickness. The combination of this plate-glass and of the object-glass may then be perfectly corrected, 60 as far as aberrations are concerned, for all the bulbs of the same type.

I have described hereinbelow and shown in accompanying drawings a form of execution of my invention as adapted for projecting sound films.

Figure 1 is a general view of the device, partly as an axial cross-section.

Figure 2 is a view at a larger scale of the bulb and its support.

Figure 3 is an end view of the slotted diaphragm forming the end of the device on the film side thereof. 70

Figure 4 is a diagrammatic cross-section through a vertical plane showing the position with reference to the slot of the light beam 75 forming on the film the image of the filament.

Figure 5 is a cross-section through a plane passing through the filament.

The bulb 1 comprises a rectilinear filament 2 stretched between two rods 2', 2'' 80 forming springs. Its cover is a cylindrical glass to one end of which is welded, without any deformation, a plate-glass 3 having parallel surfaces optically machined. The light passing through the plate-glass falls 85 on the object-glass 4 which forms an image of the filament at 5 (Figure 4) on the film 5'.

The diaphragm, provided with a slot 6, allows the beam from the filament to pass without cooperating in defining the said 90 beam and stops the parasitical light rays reflected by the walls of the bulb and forming an annular light spot, the inner diameter of which is much larger than the slot.

To provide the correct positioning of the 95 image of the filament on the band and to set it perpendicularly to the longitudinal axis thereof, the following adjusting means are provided. The socket of the lamp is provided with a rotula 7 adapted to rotate with 100 somewhat considerable friction in the recess 8 of a part integral with the plug 9. This rotula may of course be replaced by a cardon suspension allowing rotation in all directions round a point. The plug 9 carries two terminals 10 leading current to the filament and may rotate with slight friction round the coaxial tube 11 secured to the projection apparatus, the set screw 12 allowing the plug 9 to be held down. On the other hand, the 105 tube 11 carries four screws 13 diametrically opposed two by two and the tips of which engage the cylindrical part of the bulb 1. The common axis of two diametrically opposed screws is parallel to the longitudinal 110 axis of the film and the common axis of the two other screws is perpendicular to the former. Lastly, the object-glass or one of its optic components is allowed a slight axial displacement which may be effected by rotating the ring 14 through a certain angle.

Obviously, by making the plug 9 rotate through a suitable angle inside the tube 11, the filament may be set perpendicularly to the longitudinal axis of the film; by acting 115 on the screws 13, the image of the filament may be brought to enter the desired location on the sound band, for instance to come into the center of the diaphragm 5, and lastly 120 the control of the ring 14 allows a correct 125 control of the image of the filament. 130

focusing of the image of the filament on the film to be provided. The number of displacements required for adjustment is thus geometrically ensured.

5. What I claim is:—

1. An illuminating device for projecting sound films, comprising a tubular part, a slotted diaphragm and an object-glass at one end thereof, means for adjusting the longitudinal position of the object-glass, an electric lamp inside the tube including a rectilinear incandescent filament and a bulb comprising a plate-glass through which the light from the filament is adapted to pass and to form, through the object-glass, an image of the filament on the film perpendicularly to the longitudinal axis thereof, a socket for the lamp, means whereby the lamp is allowed to rotate in all directions round a point of the socket, and adjustable screws holding the lamp inside the tube. 70
2. In an illuminating device for projecting sound films, wherein the image of a rectilinear filament is formed on the film perpendicularly to its longitudinal axis, an electric lamp constituted by a cylindrical bulb containing the rectilinear filament and closed in front of the filament by a plate glass with parallel sides optically machined, an object glass forming with the plate glass, an optic arrangement without aberration projecting on the film the image of the filament, means for stopping the parasitical light rays, means for adjusting in good position the object glass and the lamp, the cylinder generating lines being perpendicular to the plane of the film. 75
3. In an illuminating device for projecting sound films, wherein the image of a rectilinear filament is formed on the film perpendicularly to its longitudinal axis, an electric lamp constituted by a cylindrical bulb containing the rectilinear filament and closed in front of the filament by a plate glass with parallel sides optically machined welded with the cylindrical part of the bulb, an object glass forming with the plate glass an optic arrangement without aberration projecting on the film the image of the filament, means for stopping the parasitical light rays, means for adjusting in good position the object glass and the lamp, the cylinder generating lines being perpendicular to the plane of the film. 80
4. In an illuminating device for projecting sound films, wherein the image of a rectilinear filament is formed on the film perpendicularly to its longitudinal axis, an electric lamp constituted by a cylindrical bulb containing the rectilinear filament and closed in front of the filament by a plate-glass with parallel sides optically machined, welded with the cylindrical part of the bulb, an object glass forming with the plate glass an optic arrangement without aberration projecting on the film the image of the filament, 85
